UNITED STATES PATENT OFFICE.

FREDERICK J. MENO, OF PORT HURON, MICHIGAN.

SHIP'S-DRAFT-INDICATING MEANS.

No. 922,933.

Specification of Letters Patent.

Patented May 25, 1909.

Application filed November 6, 1905. Serial No. 286,168.

To all whom it may concern:

Be it known that I, FREDERICK J. MENO, a citizen of the United States, residing at Port Huron, in the county of St. Clair and State of Michigan, have invented a new and useful Improvement in Ships' - Draft - Indicating Means, of which the following is a specification.

In the rapid loading of bulk cargo such as grain or ore, into vessels from bins or pockets and especially where either the cargo is not trimmed at all or is only roughly distributed by mechanical devices, it is very essential that the boat be kept on as level a keel as is possible, and that at no time the cargo be concentrated fore, aft or amidships in order to avoid straining the hull. Furthermore, it is desirable that the boat be at proper trim for best speed and control. It is also necessary when approaching a shoal spot, that the exact draft of the vessel, both forward and aft, be known, especially when the water depth and the draft approach each other as closely as they do on the Great Lakes system where boats are often loaded to within an inch or so of the water depth at the bars or shoals along the course and where the boats are of extreme length compared with their depth.

This invention relates to means for indicating a ship's draft at different points along the hull, either when the boat is stationary or under way, whereby the commanding officer may without stirring from his post either in the navigator's room or other station, instantly obtain the knowledge he desires.

The invention consists in the matters hereinafter set forth, and more particularly pointed out in the appended claim.

In the drawings, Figure 1 is a view in cross-section of a vessel's hull equipped with an indicating system embodying features of the invention. Fig. 2 is a diagrammatic view in side elevation of the vessel.

Referring to the drawings, 1 indicates a ship's hull of conventional standard construction having an outer skin or shell plating 2, tank top 3, brackets 4, stanchions 5, and other frame members. An upright tube 6 extends from the skin through the tank top near the stem, being secured by flanges 7, its lower end being open and the upper end closed by a screw cap or plug 8, similar tubes 9 and 10 being likewise secured amidships

and astern, near the keelson 11, and therefore practically at the center line of the boat.

A line 12 of piping tapped preferably into the side of the forward pipe 6 near its upper end above the tank top, leads to a pressure indicator gage 14 in the wheel house 15 of the vessel or other convenient observation station through a control or shut off valve 16, and gage cock 17. Similarly, the tubes 9 and 10 are connected to the gage 14 through piping lines 18 and 19 respectively, shut-off 65 valves 20 and 21, and the gage cock 17.

An air pressure tank 22 charged from the ship's compressor or any other suitable source, is likewise connected by piping 23 so arranged as to be opened into any of the other lines and gage, preferably as indicated, a tank pressure gage 24 being placed so as to be thrown momentarily into communication with the tank through a suitable valve 25, the valves and gages all being assembled so as to be within easy reach of the operator and collectively forming an observation station. It is evident that variations in the water line of the boat will cause variations in the pressure exerted on the gage, one inch increase 80 in depth causing a certain deflection in the gage indicator; accordingly the gage reads in feet and inches corresponding to pounds pressure of displaced water in the submerged pipes which are always below the water 85 level.

In operation, the tank gage is first momentarily opened to see that there is operative pressure in the tank, that is, enough to displace water from any of the pipes, then any 90 one of the open ended pipes is connected with the tank and with the indicator gage, the water being forced out of the pipe by the compressed air and the indicator moving until the water is all out when it stands stationary, thereby showing directly in feet and inches the depth of water displaced. When the mark at which the indicator stands is noted the valve is closed to prevent needless waste of air. The capacity of the tank is 95 sufficient so that this operation can be repeated a number of times without materially affecting the pressure therein; the tank, however, is kept filled, as before stated, from the ship's compressor or from any other 100 available source. Thus the officer in charge can tell at a moment without trouble the draft of the vessel, either forward, aft or

amidships, waves not disturbing the gage, and motion of the vessel through the water not affecting it. Obviously tubes may be inserted at as many points as desired along the 5 hull.

One feature of the invention is the arrangement of the piping whereby the submerged tubes may be cleared if fouled, by the removal of the plugs closing the upper ends 10 and the insertion of proper cleaning implements therethrough.

Obviously, the details of the invention may be varied without departing from the spirit of the invention, and I do not limit 15 myself to any particular form or arrangement of parts.

I claim as my invention:—

Ship's draft indicating means comprising the combination with a vessel's hull, of a 20 plurality of tubes within the hull at intervals along the bottom secured at their lower

open ends in the outer skin of the hull, a pneumatically operated indicator gage at an observation station in the hull remote from the tubes, pipes connecting each tube with 25 the gage, a controlling hand valve in each pipe at the station near the gage, an air pressure tank in the hull, a pressure gage therefor at the observation station, a single line of pipe connecting the tank with the indicator 30 gage and with the pressure gage, and a shut off valve for the pressure gage at the station, said controlling valves each being adapted to throw its pipe into simultaneous communication with the indicator gage and the tank 35 pipe, and said valves and gages being within operative range of a person at the station.

FREDERICK J. MENO.
